US0D1106241S

(12) **United States Design Patent** (10) Patent No.: **US D1,106,241 S**
(45) Date of Patent: ** Dec. 16, 2025

(54) **DISPLAY SCREEN OR PORTION THEREOF
WITH ICON FOR GLUCOSE MONITORING**

(71) Applicant: **Allez Health Inc.**, Carlsbad, CA (US)

(72) Inventors: **Hubert Hausegger**, Encinitas, CA
(US); **Eli Reihman**, San Diego, CA
(US)

(73) Assignee: **Allez Health Inc.**, Carlsbad, CA (US)

(**) Term: **15 Years**

(21) Appl. No.: **29/949,842**

(22) Filed: **Jun. 28, 2024**

(51) LOC (15) Cl. **14-04**

(52) U.S. Cl.

USPC **D14/486**

(57) **CLAIM**

The ornamental design for a display screen or portion thereof with icon for glucose monitoring, as shown and described.

DESCRIPTION

FIG. 1 is a front view of a display screen or portion thereof with icon for glucose monitoring; and,
FIG. 2 is a front view of a second embodiment thereof.
The broken lines showing a display screen form no part of the claimed design. All other broken lines showing portions of the graphical user interface form no part of the claimed design.
The grayscale shading depicts a contrast in appearance.

1 Claim, 2 Drawing Sheets
